US00D899895S

(12) **United States Design Patent** (10) **Patent No.:** **US D899,895 S**
(45) **Date of Patent:** **** Oct. 27, 2020**

(54) **SURFACE MOUNT**

(71) Applicant: **House of Atlas, LLC**, Evanston, IL (US)

(72) Inventors: **Jason Moss**, Libertyville, IL (US); **Alan Arthur Ford**, Sturgis, MI (US)

(73) Assignee: **House of Atlas, LLC**, Evanston, IL (US)

(**) Term: **15 Years**

(21) Appl. No.: **29/638,089**

(22) Filed: **Feb. 23, 2018**

(51) LOC (12) Cl. **08-08**

(52) U.S. Cl. **D8/349**

(58) **Field of Classification Search**

USPC D6/672, 684, 680, 683.1, 703.5; D8/349, D8/354, 355, 330, 331, 333, 380
CPC F16B 5/00; F16B 5/02; F16B 12/50

(57) **CLAIM**

The ornamental design for a surface mount, as shown and described.

DESCRIPTION

FIG. 1 is a front perspective view of a surface mount in accordance with a first embodiment of our new design; FIG. 2 is a bottom perspective view of the design of FIG. 1; FIG. 3 is a bottom plan view of the design of FIG. 1; FIG. 4 is a rear side elevation view of the design of FIG. 1; FIG. 5 is a left side elevation view of the design of FIG. 1; FIG. 6 is a top plan view of the design of FIG. 1; FIG. 7 is a right side elevation view of the design of FIG. 1; FIG. 8 is a front side elevation view of the design of FIG. 1; FIG. 9 is a front perspective view of a surface mount in accordance with a second embodiment of our new design; FIG. 10 is a bottom perspective view of the design of FIG. 9;

FIG. 11 is a bottom plan view of the design of FIG. 9; FIG. 12 is a rear side elevation view of the design of FIG. 9; FIG. 13 is a right side elevation view of the design of FIG. 9; FIG. 14 is a top plan view of the design of FIG. 9; FIG. 15 is a left side elevation view of the design of FIG. 9; and, FIG. 16 is a front side elevation view of the design of FIG. 9.

The broken line showing in FIGS. 2, 4, 10 and 11 is included for the purpose of illustrating portions of the surface mount that forms no part of the claimed design.

1 Claim, 8 Drawing Sheets
